Attorney.

UNITED STATES PATENT OFFICE.

CARL F. BREHMER, OF PHILADELPHIA, PENNSYLVANIA.

TRICK FAN.

1,407,836.

Specification of Letters Patent. Patented Feb. 28, 1922.

Application filed December 9, 1920. Serial No. 429,366.

To all whom it may concern:

Be it known that I, CARL F. BREHMER, a citizen of the United States, residing at Philadelphia, in the county of Philadelphia and State of Pennsylvania, have invented 5 certain new and useful Improvements in Trick Fans, of which the following is a specification.

My invention relates to trick fans, that is 10 to say, to that type of fan which, when opened in one direction, will present the appearance and will be serviceable as an ordinary fan, but which, when opened in a contrary direction, appears to be broken and in 15 separated segments. Heretofore, in the construction of fans of this type, it has been usual to make the ribs thereof of thin wooden splints to which the web portions were united by glue or other suitable adhesive. 20 When the fan so constructed was used for its intended purpose, persons who were unfamiliar with the proper method of manipulation of the fan would, in their bewilderment, frequently subject the same to improper strains which would result in the 25 actual destruction of the fan, either by breaking the wooden ribs or by causing the web to be pulled from the ribs at the place of attachment thereto.

The object, therefore, of my present invention is to provide an improved trick fan of the type above mentioned, which will be so constructed and arranged as to be more durable than those at present in common use, 35 and which, at the same time, may be inexpensively constructed.

The nature and characteristic features of 40 my invention will be more readily understood from the following description taken in connection with the accompanying drawings forming part hereof, in which—

Figure 1 is an elevational view of a fan embodying the main features of my present invention, the same being shown opened in 45 the direction to cause the same to assume the appearance of an ordinary fan;

Fig. 2 is a similar view showing the same opened in the contrary direction, to cause the separate segments thereof to become 50 separated;

Fig. 3 is a fragmentary perspective view of a portion of the fan in the condition shown in Fig. 1;

Fig. 4 is a similar view in the condition 55 shown in Fig. 2; and

Fig. 5 is a fragmentary detail sectional view, enlarged, taken approximately on the line 5—5 of Fig. 1.

Referring to the drawings, the fan comprises a plurality of sector-shaped webs, 60 preferably made of textile material. Each sector is provided with two ribs 7 and 8 respectively, to which the side margins of the sector-shaped web portions are united in a manner to be presently described. The trick 65 effect is obtained by the peculiar manner of pivoting the ribs 7 and 8 of each sector with respect to the corresponding ribs of adjoining sectors, the arrangement being such that the ribs 7 and 8 of each sector have disposed 70 between the same, at the pivot 9, one rib 7 of one adjoining sector and the rib 8 of the other adjoining sector. By this arrangement, when the fan is opened in one direction, there will result an interlocking 75 between the rib 7 of any particular sector and the rib 8 of the next adjoining sector, the respective web portions 6 serving to prevent displacement of the ribs beyond each other; whereas, when the fan is opened in the contrary direction, the respective segments will 80 be free to separate as shown in Fig. 2 of the drawings.

The present invention, however, relates more particularly to the construction of the 85 ribs and the manner of joining the sector-shaped web portions thereto. The ribs 7 and 8 are preferably made of sheet metal, having three folds, the folds being formed by creasing the sheet metal longitudinally. 90 The side margins of the sector-shaped web portions 6 are included within the folds of the sheet metal forming the ribs 7 and 8, so as to effectively clamp the same thereto.

By the foregoing arrangement, the web 95 portions will be securely attached to the ribs and will be maintained properly connected thereto, notwithstanding the rough usage to which the device may be put. Furthermore, it will be found that the ribs will be much 100 stiffer than the wooden splints commonly used heretofore for such purpose, but if, however, the same should be subjected to such undue stress as to become bent, the same may be readily straightened.

It will be seen that there is thus provided an improved form of trick fan of the type above referred to, which may be inexpensively constructed, but which will be found to be quite durable in use, notwithstanding 110

the rough usage to which a device of this type will naturally be put when used for its intended purpose.

Having thus described the nature and 5 characteristic features of my invention, what I claim as new and desire to secure by Letters Patent, is:

A trick fan comprising a plurality of sections each comprising a sector shaped web 10 portion and ribs to which the side margins of the web portions are attached, the ribs being so pivoted to each other that when the fan is opened in one direction the web por-

tions will limit the movement of the ribs and thereby form a fan of ordinary appearance and utility, but when opened in the opposite direction will permit the several sections to swing clear of each other, the ribs being formed of longitudinally creased and folded sheet metal, and the side margins 15 of the web portions being clamped in the folds of said ribs.

In testimony whereof, I have hereunto signed my name.

CARL F. BREHMER.
